(57) **CLAIM**

The ornamental design for a balance feedback device, as shown and described.

DESCRIPTION

FIG. 1 is a perspective view of the balance feedback device. FIG. 2 is a top view of the balance feedback device.

FIG. 3 is a perspective view of the balance feedback device.

FIG. 4 is a side view the balance feedback device.

FIG. 5 is a back view of the balance feedback device.

FIG. 6 is a side view of the balance feedback device.

FIG. 7 is a perspective view of the balance feedback device.

FIG. 8 is a bottom view the balance feedback device; and,

FIG. 9 is a perspective view the balance feedback device.
